(57) **CLAIM**

The ornamental design for a data connector housing, as shown and described.

DESCRIPTION

FIG. 1 is a perspective view of a data connector housing showing our new design, taken from the top-front and to the side:

FIG. 2 is another perspective view of the data connector housing of FIG. 1, taken from the top-rear and to the side;

FIG. 3 is another perspective view of the data connector housing of FIG. 1, taken from bottom-front and to the side; FIG. 4 is another perspective view of the data connector housing of FIG. 1, taken from the bottom-rear and to the side; FIG. 5 is a front elevation of the data connector housing of FIG. 1; FIG. 6 is a rear elevation of the data connector housing of FIG. 1; FIG. 7 is a top plan view of the data connector housing of FIG. 1; FIG. 8 is a bottom plan view of the data connector housing of FIG. 1; FIG. 9 is a right side elevation of the data connector housing of FIG. 1; FIG. 10 is a left side elevation of the data connector housing of FIG. 1; FIG. 11 is a perspective view of another data connector housing showing our new design, taken from the top-front and to the side; FIG. 12 is another perspective view of the data connector housing of FIG. 11, taken from the top-rear and to the side; FIG. 13 is another perspective view of the data connector housing of FIG. 11, taken from bottom-front and to the side; FIG. 14 is another perspective view of the data connector housing of FIG. 11, taken from the bottom-rear and to the side; FIG. 15 is a front elevation of the data connector housing of FIG. 11; FIG. 16 is a rear elevation of the data connector housing of FIG. 11; FIG. 17 is a top plan view of the data connector housing of FIG. 11; FIG. 18 is a bottom plan view of the data connector housing of FIG. 11; FIG. 19 is a right side elevation of the data connector housing of FIG. 11; FIG. 20 is a left side elevation of the data connector housing of FIG. 11; FIG. 21 is a top-front perspective view of the data connector housing of FIG. 11 shown in an exemplary operating environment; and, FIG. 22 is a bottom-front perspective view of the data connector housing and operating environment of FIG. 21. The broken lines are included for the purpose of illustrating portions of the data connector housing that form no part of the claimed design.

1 Claim, 11 Drawing Sheets
